CRYSTAL FILTER OF VARIABLE BAND
WIDTH

Hans Goering, Berlin, Germany, assignor to Tele-funken Gesellschaft für Drahtlose Telegraphie m. b. H., Berlin, Germany, a corporation of Germany

Application February 15, 1939, Serial No. 256,459
In Germany March 18, 1938

5 Claims. (Cl. 178—44)

It is known in the art that the band width of crystal filters may be varied by making the crystal the series element between two parallel resonance circuits connected as shunt elements, one of the two resonance circuits, or both of them, being detuned in reference to the frequency passed by the crystal or else by varying the coupling between the two oscillatory circuits and the crystal. At all events, the parallel capacitance of the crystal is neutralized by a bridge scheme or else by connecting in parallel a coil dimensioned so as to insure resonance at the transmitted frequency. However, such arrangements inhere the drawback that the resonance curve is monowave (has only one hump) only for a limited band width, and that it exhibits two resonance points or two waves whenever the band width increases. The maximum band width which is possible is then limited by the admissible crevassing of the resonance curve. Now, this shortcoming is obviated by the present invention. In other words, the invention has the advantage that for different band widths the characteristic form of the resonance curve is preserved without it being necessary to replace the crystal itself. The characteristic shape of several resonance curves is the same if, for a definite ordinate value, the band widths of the various curves differ from one another by the same factor as for any other ordinate value at all, in other words, that is, bear the same ratio. The slopes or sides of the curves, that is to say, the widths of the transition intervals, referred to the band width are equal to one another for a certain ordinate value.

The invention is concerned with a crystal filter which consists of a crystal and which forms the line or series element between two parallel resonance circuits connected as shunt arms or elements, the crystal being neutralized. According to the invention, to the end of increasing the band width, the ratio between the inductance and the capacity of the parallel resonance circuits being tuned to the pass-band frequency for all band widths is raised, and to increase at the same time the terminating resistance at both ends in such a way that the ratio of each of the terminating resistances to the increased surge impedance of the filter and thus also the characteristic form of the resonance curve of the filter are preserved.

The invention is particularly useful in the I. F. part of superheterodyne receivers, for in the operation of these it is often necessary to make adjustments so that, at will, very narrow resonance curves for telegraphic signal reception and broad

resonance curves presenting steep flanks for telephonic reception can be received. The quartz crystal which is most important for practical use, is important in connection with quartz filters, by the way, not only for the purpose of obtaining very narrow or pointed resonance curves, but it is required, because of its low losses also so as to secure great steepness, that is, a narrow transition interval, for broad resonance curves, since series resonance circuits for the line elements of 10 RF filter circuits have heretofore not been designed with such low losses in any other manner. 5

Fig. 1 shows the fundamental layout of the filter circuits. Fig. 2 is an exemplified embodiment of the invention, while Fig. 3 shows resonance curves obtained with the filter of the invention. 15

Referring to Fig. 1, S is an A. C. source of current whose E. M. F. is denoted by E and its internal resistance by R₁. This internal resistance 20 in the present scheme serves as a terminating resistance of the input end of the filter. Inductance L₁ and capacities C₁ and C₅ represent the equivalents of the quartz crystal (disregarding losses). The parallel capacity C₅, by some ways 25 and means known in the art, say, by the bridge scheme as shown comprising the coil L₄ and capacity C₄ is neutralized, that is to say, rendered ineffective. What then remains is only the series resonance circuit L₁, C₁, which conditions the 30 pass wave transmitted by the crystal. Now, this quartz crystal is connected as a line or series mesh between two parallel resonance circuits L₂, C₂, and L₃, C₃. The terminating resistance at the output end is designated by R₂. 35

In Fig. 2 which is an exemplified embodiment of the invention, the quartz filter is inserted between two tubes. The parallel capacity of the quartz crystal Q also here has been neutralized, though this is not specifically indicated. As to 40 the rest, the references are the same as in Fig. 1. For changing the band width which is here effected by steps, though it could just as well be effected continuously, there are provided four switches S₁—S₄. The parallel oscillation circuits 45 L₂—C₂, and L₃—C₃, are all tuned to the pass wave of the crystal, and they distinguish themselves only by differences in the ratio of inductance to capacity as indicated by the sizes chosen for the coils and the condensers. In a similar way, the 50 various sizes of the terminating resistances are schematically represented in the drawing. In calculating the resistances R₁ and R₂, of course, the parallel internal resistance of the first tube or the input resistance of the second tube as well 55

as the natural damping resistances of the oscillation circuits imagined to be connected in parallel to the oscillation circuits must be considered, for it will be understood that the terminating resistances are composed of all of these resistances. In the left-hand position of the switches, the filter is set to the widest band, and in the right-hand position to the narrowest band.

It shall now be shown in what way, by the aid of the quadripole or four-terminal network theory, it is possible to demonstrate that by the ways and means hereinbefore described, the band width is variable, while yet the characteristic form of the resonance curve is incidentally preserved.

In what follows, $\omega_1 < \omega_2$ are to denote the limiting or cut-off frequencies of the range in which the quadripole damping becomes zero; Z_m is the surge impedance at mean frequency

$$20 \quad \omega_m = \sqrt{\omega_1 \omega_2}$$

and

$$25 \quad b = \frac{\omega_2 - \omega_1}{\omega_m}$$

the relative width of gap or interval in the sense of the theory underlying four-terminal networks. The said "gap" width as will be remembered, is the band-pass of the filter in the theoretical case, which, in actuality, never arises, that the filter for all frequencies is terminated with a resistance which is equal to surge impedance of the filter which generally is a function of the frequency. The damping curve according to the theory of quadripoles would then be an exact measure for the resonance curve.

In the light of the theory of four-terminal networks, the relations between the circuit elements $L_1, C_1, L_2, C_2, L_3, C_3$ of the filter Fig. 1 and its characteristic quantities Z_m, b and ω_m are expressible by the following four equations:

$$45 \quad (1) \quad L_1 = \frac{2 \cdot Z_m}{b \cdot \omega_m} \quad (2) \quad C_1 = \frac{b}{2 \cdot \omega_m \cdot Z_m}$$

$$(3) \quad L_2 = L_3 = \frac{b \cdot Z_m}{\omega_m} \quad (4) \quad C_2 = C_3 = \frac{1}{\omega_m \cdot b \cdot Z_m}$$

Now, the demand is that the crystal, regardless of the band width, should stay unaltered so that L_1 and C_1 would be constant. The result of this condition is (as shown by the first Equations 1 and 2) that the relation between Z_m and b remains unvaried provided that the mean frequency ω_m , which, in the case of a receiver is equal to the I. F. stays constant. In other words, the surge impedance Z_m for the mean frequency ω_m of the filter, when the gap width b is doubled, is also doubled of necessity. Both these changes, as can be noted from Formulae 3 and 4 are brought about by quadrupling L_2 and L_3 , while cutting C_2 and C_3 to one-fourth. The resonance frequency of the parallel resonance circuits remains unaltered no matter what the gap width. This, in the first place, shows that width b is alterable by changing the ratio of L_2 to C_2 , and of L_3 to C_3 .

The fact that also the characteristic form of the resonance curve is preserved, no matter what the band width, in the presence of conditions as outlined, can be shown by the following equation of the resonance curve which is also calculable by the aid of the theory of four-terminal networks. The following equation shows the absolute value 75 of the relation between output current to input

E. M. F. as a function of the relative and actually existing band width B .

$$5 \quad \left| \frac{I}{E} \right| = \frac{1}{2 \cdot n \cdot Z_m} \cdot \frac{1}{\sqrt{1 + \frac{B^2}{n^2 \cdot b^2} \left(1 - n^2 + \frac{n^2 \cdot B^2}{b^2} \right)^2}}$$

where

$$10 \quad n = \frac{R_1}{Z_m} = \frac{R_2}{Z_m}$$

$$15 \quad B = \frac{\omega}{\omega_m} - \frac{\omega_m}{\omega}$$

B stands for the relative band width for different ordinate values in Fig. 3, that is to say, the actually existing band width referred to the mean frequency ω_m , contradistinct from the gap width b in the sense of the four-terminal network theory existing in the ideal case. For this filter, at the value of

$$20 \quad \frac{1}{\sqrt{2}} \approx 0.7$$

times the crest of the resonance curve, the actual band width B is equal to the gap width b according to the four-terminal network theory (marked by dots in Fig. 3).

The equation for the resonance curve shows that the characteristic form of the resonance curve, for different widths b is always the same, if the ratio n between the various terminating resistances R_1 and R_2 to the surge impedance Z_m of the filter stays the same. For then the shape of the resonance curve is solely a function of the relation between the actual band width B and the gap-width b occurring twice in the root of the denominator. Thus, if the gap-width b by varying the ratio of LC of the parallel resonance circuits is raised, say, from .1 to .3 (see Fig. 3) and if the terminating resistances are correspondingly changed, then, according to the equation of the resonance curve, the actual relative band width B , for all co-ordinate values, is trebled. The characteristic form is then the same as before inasmuch as, in line with what has been pointed out, it is determined only by the relation n between the terminating resistances R_1 and R_2 and the surge impedance Z_m . If the said ratio is equal to unity there results a resonance curve which approaches the rectangular form most closely. But the resonance curve becomes triple-humped (three-wave) if n exceeds 1 (overmatching). But the crevasses, contradistinct to known quartz filters, do not grow as the band width grows since the form of the resonance curve stays unvaried with constant n .

The output potential of the filter, for a constant input potential, is the same for all band widths. For it will be noted that for the mean frequency of the filter, the parallel resonance circuits may be assumed to be non-existent, while the series resonance circuit may be conceived as being short-circuited. What then remains in the circuit arrangement Fig. 1 are merely the two terminating resistances which, no matter what the band widths, are equal to each other, with the result that at the output resistance there arises always the same output potential. Referring again to Fig. 2, if the first tube has a high internal resistance (pentode), then, in the presence of a constant grid alternating potential of this tube, the output potential of the filter increases practically in the same measure as the band width because of the fact that, as the band width grows, the terminating resistances are 75

raised in the same ratio, and that the plate alternating voltage rises correspondingly.

What I claim is:

1. An electrical wave filter network comprising a crystal element in the series arm of a π -type filter, the shunt arms of which are each constituted by a selected one of a plurality of parallel resonant circuits, said circuits being tuned to the same operating frequency of the filter network but having different ratios of inductance to capacity.
2. An electrical wave filter network according to claim 1 wherein each shunt arm is adapted to have a selected one of a plurality of terminating impedances connected thereacross.
3. An electrical wave filter network comprising a crystal element which constitutes the series arm of a π -type filter, a plurality of resonant circuits tuned to the same operating frequency of the filter network arranged for selective connection to one side of the crystal element to constitute one of the shunt arms of the filter network, corresponding parallel resonant circuits arranged for selective connection to the other side of the crystal element to constitute the other shunt arm, the circuits of each shunt arm having different ratios of inductance to capacity, and means for selectively connecting corresponding resonant circuits as shunt arms for the filter network whereby the band width of the network

may be varied without altering the shape of the resonance curve.

4. An electrical wave filter network according to claim 3, wherein the parallel resonant circuits of each shunt arm are arranged in the order of their decreasing ratios of inductance to capacity, the pass band of the filter being widest when the resonant circuits with the highest inductance to capacity ratio are operative, and the pass band being narrowest when the resonant circuits with the lowest inductance to capacity ratio are operative.

5. A crystal filter of variable band-pass width, comprising a crystal element which serves as the coupling element between a pair of vacuum tubes, a plurality of parallel resonant circuits tuned to a common frequency and arranged for selective connection between the anode and cathode of the first tube and between the signal grid and cathode of the second tube, corresponding pairs of said resonant circuits having a different inductance-capacity ratio from the others, a plurality of terminating resistances of different values arranged to be selectively shunted across each of the resonant circuits, and means for selectively switching in corresponding resistances and resonant circuits in cooperative relation with said crystal element.
